[57] CLAIM

The ornamental design for a swim teaching aid, as
shown and described.

DESCRIPTION

FIG. 1 is a side elevational view of a swim teaching aid
in reduced scale showing my new design, the broken
lines are for illustrative purposes only;

FIG. 2 is a top plan view thereof;

FIG. 3 is an end elevational view thereof, the opposite
end elevational view being a mirror image;

FIG. 4 is a bottom plan view thereof;

FIG. 5 is a side elevational view thereof, the opposite
side being a mirror image; and,

FIG. 6 is a bottom and side perspective view thereof.

FIG. 1

FIG. 2

FIG. 3
